INTERNAL COMBUSTION ENGINE

Jean A. H. Barkeij, Altadena, Calif.

Application October 27, 1933, Serial No. 695,459
Renewed January 23, 1939

19 Claims. (Cl. 123—48)

This invention relates to internal combustion engines and more particularly to engines of the aircraft type, being particularly embodied in engines of the radial cylinder type, though obviously the principles of the invention may be incorporated in engines other than those of the type specified. An object of this invention is to control the compression ratio of such engines by utilizing not only an automatic control mechanism for varying the relative position of the piston in the engine cylinder by means of eccentric sleeves on the crankpin as the piston is positioned in its outermost position of travel to increase or decrease the clearance space of the pistons in the cylinders by means of centrifugal weights on said eccentric sleeves, or by weights on pinions geared to said eccentric sleeve on the other side of the axis of the crankshaft. This is accomplished in the present embodiment of the invention by providing a control whereby to relatively shift the connecting rod with respect to the crank by means of a relatively adjustable eccentric bearing for the inner end of said connecting rod.

Another object of the present invention is to provide an engine of improved operating performance by providing means whereby to effect an improved balance to the engine by incorporating opposed counterweights to compensate for the disturbance of the running balance of the rotating and reciprocating parts caused by the movement of the eccentricity of said sleeves on said crank-pin bearings.

Still another object of the present invention is to provide mechanical means to control the action of said automatic means, or hydraulic means or in general fluid pressure means to counteract or to control the automatic means to vary the clearance space of the pistons in the cylinders.

A still further object of the present invention resides in the detailed means for accomplishing the aforesaid objects, and in particular, it will be noted that means are provided whereby to accomplish the objects aforesaid independent of the engine speed.

In many instances the compression ratio of engines is desired to be increased as the engine speed increases, while in some instances, it will be noted that it is more desirable to decrease the compression ratio as the engine speed increases. In the Figs. 1, 2, 8, 9 and 14 I show constructions whereby the centrifugal weights on eccentric sleeves are so placed that the compression ratio is decreased at high speeds (that means the compression space is increased at high speeds) and in

Figs. 3, 5, 6, 7, 12 and 13 the reverse arrangements are shown whereby the compression ratio is increased at high speeds (that means the clearance space is decreased at high speeds).

By such means the center of gravity of the reciprocating parts are seriously displaced and for that reason I associate such sleeves with counterweights opposite the crankpins carrying such sleeves to counterbalance and eliminate said unbalance caused by the rotation of such an eccentric sleeve, and parts associated therewith.

In certain structures I have geared the eccentric sleeve to such counterweights as shown in Figs. 1, 2 and 14 so that the unbalance caused by the rotation of the eccentric sleeve is rigidly proportioned by said mechanical relation. If the compression is increased or decreased at high speeds the counterweights can move accordingly.

In other structures as shown in Fig. 3 I have compensated said unbalance by gearing the eccentric sleeves to each other on crankpins arranged at 180° to each other. Such a compensation is not so perfect as that shown in the Figs. 1, 2 and 14 because the planes of the two reciprocating and rotating masses are not aligned. Equally here the counterweights may move farther or closer to the axis of the crankshaft.

In Figs. 7, 8, 9, 10, 11 I counterbalance the said displacement of the reciprocating masses automatically, there being no direct mechanical relation between the rotation of the eccentric sleeve and the movement of said counterweights. These hydraulic means, however, cause again a rigid relation between the rotation of the sleeve and the counterbalancing.

In Figs. 12 and 13 I show a construction somewhat similar thereto, only with this difference that the auxiliary counterweights are further associated with hydraulic means to control the action of the weights on the eccentric sleeves.

In all these constructions it is understood that the reciprocating parts are per se counterbalanced by main counterweights arranged diametrically opposite the crankpins carrying such parts. The auxiliary counterweights, however, being so arranged and moving towards or away from the axis of the crankshaft in a direction opposite to the direction in which the center of gravity of the reciprocating masses move in response to the rotation of the eccentric sleeve, either away from or towards the axis of the crankshaft.

Therefore if the eccentric sleeve is so arranged that the center of gravity approaches the center of the crankshaft at high speeds, lowering the compression ratio and increasing the compres-

sion space, it stands to reason that the auxiliary counterweights should be moved inwardly and when the eccentric sleeve is so arranged that at high speeds the compression ratio is increased 5 and the compression space decreased, it stands to reason that the auxiliary weights should be moved outwardly to compensate for said unbalance.

Therefore only the constructions shown in 10 Figs. 1, 2, 14, 3 and 4 are adaptable to both constructions, while the other arrangements in which the auxiliary counterweights always move automatically outwardly, the centrifugal force on one 15 side of the crankshaft always increasing, are only adaptable to the eccentric sleeve so arranged that the compression increases at high speeds.

It is therefore also understood that the hydraulic arrangement of Fig. 5, combined with the structure of Figs. 12 and 13, may control the fly- 20 weights and counterweights 80 entirely, without the further structure of the gearing to control eccentric bearings and the variable compression mechanically. Likewise, the hydraulic arrangement may control the amount of pressure on the 25 right and left side of the plunger 80 entirely, with and without the spring 81. In the latter case it stands to reason that the flyweights 71 can be made of any size, and they may rotate said eccentric sleeve at practically any speed at 30 which the engine will operate. The omission of the spring 81, does not alter the automatic character of the mechanism to create a variable compression engine, because the variation thereof still depends on and acts in response to centrifugal 35 force. The addition of the spring 81 to this mechanism and to the hydraulic control arrangement certainly does not make it automatic. The difference is purely a matter of degree. If a spring 81 urges the piston 80 always to the right 40 to check the rotation of the eccentric sleeve to increase the compression ratio, this increase will take place merely at a higher speed. If it is omitted the centrifugal force may establish said increase at all speeds of which the engine is 45 capable. This is of extreme importance because the increase of compression may be useful at low speeds to increase the temperature of the charge, especially in compression-ignition engines, and it is equally useful at high altitudes to keep the 50 maximum compression degree necessary for said temperature in compression-ignition engines, or necessary for high thermal efficiency of explosive engines at high speed, or for such efficiency of such engines at high altitudes at low speeds.

55 Therefore my mechanism to increase the compression can be made virtually independent of speed, that is independent of the speed at which any internal combustion will function properly, that is at a minimum of 200 to 300 R. per minute, 60 because I control either hydraulically, or mechanically, an automatic increase by the operator.

Therefore in general I have illustrated and will describe three major methods. The pure hydraulic, the pure mechanical, the pure automatic type. Besides these three, there are several cross combinations possible, a few of which are referred to and will be referred to, which type is to be preferred depends upon the type of motor, type of service, and further upon design.

70 It stands to reason that this compensating action of the auxiliary counterweights is of greater importance in the radial type of engine, because the masses attached to the crankpin or crankpins are considerably greater than in the in-line-type engine. However, even in the latter type,

provided with a great number of crankpins the present invention is of the utmost importance in constructing a practical, variable-compression engine, which will operate satisfactorily at all speeds, and without vibration.

5 In Fig. 7 I show further mechanical means to control the action of the automatic means to vary the compression. The mechanical means being controlled by the operator during the operation of the engine. The mechanical means may control the movement of the counterweight likewise, as in Fig. 13.

10 Fig. 13 I show hydraulic means to control the action of the automatic means to vary the compression and the action of the counterbalancing 15 means during the operation of the engine.

20 In Fig. 5 I show means to increase the resistance of elastic spring means, associated with the automatic means to vary the compression during the operation of the engine.

25 The mechanical means of Fig. 5 may be further controlled hydraulically by the means shown in Figs. 12 and 13.

30 The arrangements whereby the higher compression is obtained at higher speeds are particularly valuable for aviation engines adapted to fly at very high altitudes in the substratosphere or stratosphere. To prevent the engine from automatically obtaining a high compression ratio at high speeds when flying in low altitudes, I incorporate a hydraulic or mechanical arrangement to prevent the automatic means from reaching such a position.

35 Reversely the arrangements whereby the higher compression ratio is obtained at lower speeds (that is decreased at higher speeds) are useful in compression ignition engines. This arrangement is further useful in engines provided with a centrifugal blower of which the charging capacity increases with the speed of rotation of 40 the engine. When the charging pressure is 10 or more inches of mercury at 3000 revs. per minute the cylinders receive a greater amount of gas than when the engine rotates at half that speed or at 300 revs. per minute, and the compression 45 has to be decreased at high speeds and increased at low speeds. But in all arrangements it is useful to control the variation of compression ratio at varying altitudes, and varying temperatures, especially in the compression ignition type of 50 engine.

55 In either case control of the automatic action to vary the compression ratio is useful, because the same internal combustion engine may perform at high or low altitudes in aviation engines. These results being readily accomplished by means disclosed and described in the present application in which the drawings illustrate preferred embodiments of the invention, and in 60 which:

65 Fig. 1 is a longitudinal sectional view through a radial engine illustrating a fragmentary portion thereof and showing the crankshaft and the connecting rods therewith, this figure being substantially taken on the line 1—1 of Fig. 2.

70 Fig. 2 is a fragmentary detail sectional view taken on the line 2—2 of Fig. 1 and illustrating the automatic control of the eccentric sleeves on the crankpin by means of centrifugal weights which are actuated in response to engine speed variations. This arrangement is entirely automatic.

75 Fig. 3 is a fragmentary elevational view of a radial engine with parts being broken away and other parts of the engine being shown in section 75

to illustrate the action of the eccentric sleeve in cooperation with the centrifugal weights which are actuated in response to engine speed for adjusting the connecting rod mountings.

5 Fig. 4 is a fragmentary sectional view of the structure illustrated in Fig. 3, said sectional view being taken substantially on the line 4—4 of Fig. 3.

Fig. 5 is a diagrammatic view which illustrates 10 another modified form of construction, particularly illustrating a construction which is adapted for employment with an in-line engine and showing further manual or mechanical means actuated manually to restrain the action of the 15 weights on the eccentric sleeves. The manual means show a pull rod 44a, which is the same rod 44 as shown in Fig. 15 where it operates equally a three way valve controlling the hydraulic means shown in Figs. 12 and 13 to control likewise the 20 action of the automatic means. These hydraulic means are not shown in the crankarms of the arrangement of Fig. 5, but those shown in Figs. 12 and 13 may be equally applied here, so that the 25 automatic action may be controlled by the operator two ways, mechanically and hydraulically.

Fig. 6 is a fragmentary sectional view illustrating 30 a further modified form of construction and showing the automatic means to rotate the eccentric sleeve on the single crankpin of a radial engine.

Fig. 7 is a diagrammatic view of a crankshaft for an in line engine illustrating mechanical means consisting of an electro-motor to control the automatic action of the centrifugal weights 35 on the eccentric sleeves on the various crankpins.

Fig. 8 is a fragmentary detail view of a crank illustrating means for automatically adjusting the location of the balancing weight and taken substantially on the line 8—8 of Fig. 9.

40 Fig. 9 is a detail sectional view taken substantially on the line 9—9 of Fig. 8.

Fig. 10 is a detail sectional view on the line 10—10 of Fig. 11 and illustrating adjusting counterweights and means for hydraulically controlling and cushioning the adjustable weights.

45 Fig. 11 is a detail sectional view taken at right angles to Fig. 10 substantially on the line 11—11 of Fig. 10.

Fig. 12 illustrates a further modified form of 50 construction embodying hydraulic means to control the automatic action of the weights on the eccentric sleeves and taken substantially on the line 12—12 of Fig. 13.

Fig. 13 is a plan sectional view of the mechanism shown in Fig. 12 and taken substantially on the line 13—13 of Fig. 12, and

Fig. 14 on sheet one is a detail sectional view of a modified construction for mounting the controlling counterweights of Fig. 1.

60 In the embodiment of the invention as shown in Figs. 1 and 2, there is provided a crankshaft structure having a shaft 1 to which is connected a crank arm 2. A shaft 5 is arranged for cooperation therewith and carries a crank arm 4, said crank arms 2 and 4 being connected by a crank pin 3. These shafts 1 and 5 are preferably supported directly in the crankcase 6 and are preferably constructed with suitable bores for supporting certain other internal shafts, thus the shaft

65 70 supports the internal shaft 7 which carries a gear 8 at its inner end that is in turn meshed with the gears 9 and 10. The gear 9 is carried by an eccentric sleeve which is mounted on the crank pin 3 while the gear 10 is connected by a shaft 10b supported in the crank arm 2. The gears

9 and 10 are thus supported for rotation and similarly gears 11 and 14 are respectively rotatably supported by crank pin 3 and crank arm 4, and are arranged to be meshed with gear 12a carried by the shaft 12 which is rotatably supported within the bore of shaft 5.

The weights 9a and 10a are respectively carried by gears 9 and 10 while the weights 11a and 14a are respectively carried by gears 11 and 14 as shown in Figs. 1 and 2. These weights are substantially the same size and weight and because of the engagement of the aforesaid gears, it will be noted that they are actuated together. The shaft 7 is surrounded by a coil spring 1a which is mounted within the enlarged bore of the shaft 1, one end of this spring being anchored to the shaft as at 7b, while the other end of the coil spring is anchored to the internal shaft 7 as at 7c, and the spring is so arranged as to angularly urge the shaft 7 in such a way as to cause the weights 9a and 10a to assume a position as shown in Fig. 2 in solid lines. Fig. 1 illustrates these weights 9a and 10a in solid lines in a position as is illustrated in Fig. 2 with the moving parts in a different position. The gear 9 is carried by the bushing or sleeve 15 which is mounted on the crankpin 3, this sleeve having an exterior surface which is eccentric with the inner bore of the sleeve. While the gear and weight 9 and 9a respectively are carried at one end of this sleeve

15 it will be noted that the present arrangement provides for a construction in which the gear and weight 11 and 11a respectively are carried on the opposite end of said sleeve, said gears and weights being secured to the sleeve in any suitable manner. The movement of said weights from the position shown in Fig. 2 in full lines, to the position shown in dotted lines is resisted by the coil spring 1a. It is preferable to incorporate another coil spring 13 around the internal shaft 12 located in the enlarged bore of the shaft 5, this coil spring 13 being fixed at one end to the internal shaft 12 as at 13a and fixed at its other end to the shaft 5 as at 13b.

The sleeve 15 is adapted to support a single connecting rod or it may be utilized for carrying the hub 16 of a master rod, said hub being provided with a plurality of knuckle pins 16a for supporting the articulated rods 16b.

It will thus be noted that as the engine speed increases the centrifugal force of the weights 9a, 10a, 11a and 14a will overcome the resistance of springs 1a and 13a and cause a rotation of the eccentric sleeve 15, this rotation of the sleeve providing an adjustment of the connecting rod mounting by varying the relative location of the knuckle pin axes with respect to the axis of the crank pin 3. This adjustment affects relative adjustment of the piston when the same is in its outermost position of travel and by accurately designing the structure, it will be noted that this control effects an increase of the clearance space of the pistons in the cylinders at high engine speeds or in other words effects a decrease of the compression ratio when the engine speed increases.

It is found desirable to supply lubricant to the various bearings and therefore the crankshaft structure is provided with a suitable oil conduit 17 to which is connected various branch conduits 18 and 19 for conducting the oil to the bearings to be lubricated.

In most instances it is found that it is desirable to employ weights of a smaller mass disposed on either side of the connecting rod structure.

- If desired, the gears associated with the sleeve charge may be further compressed to maintain the engine power output the same as is had in lower altitudes with a lesser compression even if supercharging means are used in combination therewith. Obviously, the present construction 5 may be used in engines of the compression ignition type as well as with engines of the spark ignition type.
- 10 that the counterweights on the parts or pinions 10a and 14a in Figs. 1 and 2 may be the only ones used, omitting the counterweights 9a and 11a on the sleeve itself. Likewise, in Fig. 14 (Sheet 1) the counterweight on the pinion 10c may be the 15 only one used, in order to save space on the sleeve itself for the connecting rod and pinion on the sleeve.

Figs. 3 and 4 illustrate a modified form of construction and in this construction it will be noted 20 that I have provided a crank structure constructed of a built-up section embodying shafts 36 and 37 which are preferably mounted in the crank case, each shaft respectively carrying crank cheeks 20 and 20a. The crank pins 21 and 25 21a are respectively carried by the cheeks 20 and 20a and each support an eccentric bearing means or sleeve 22 and 22a. The crank pins overlap as shown in Fig. 4 and are connected by a crank arm 23, said crank arm being preferably 30 formed in two sections and clamped together and to the crank arms by means of suitable bolts 24. The crank arms are preferably provided with annular grooves 23b. The crank arm supports a shaft 25 lying intermediate the crank pins 21 and 35 21a and carries a gear 26 at one end and a gear 27 at the other end. The gear 26 is arranged to mesh with the gear 28 carried by the eccentric sleeve or bearing 22 while the gear 27 is arranged to mesh with the gear 29 carried by the eccentric 40 sleeve or bearing 22a. The sleeve 22 carries the weight 30 while the sleeve 22a carries a weight 30a, and it will be obvious that as the engine speed increases these weights 30 and 30a have a tendency to fly outwardly from the center of their 45 rotation, this centrifugal force actuating the shaft 25 and rotating same. A coil spring 31 surrounds the shaft 25 and is constructed to have one end bearing against a shoulder 25a carried by the shaft 25 while the other end of said spring 50 is arranged to bear against the crank arm 23 as at 23a.

The arrangement and operation of the present construction is such that as the weights 30 and 30a are moved outwardly in response to the 55 centrifugal forces due to the rotation of the crankshaft they tend to expand the coil spring 31 into friction engagement with the crank arm 23 thereby increasing the resistance to the movement of said weights and adjustment of said eccentric sleeves 22 and 22a and preferably the friction between the coil spring 31 and crank arm 23 is such as to build up sufficient resistance to prevent the weights from actually reaching their extreme outer position and obviously the maximum adjustment may be predetermined by selecting a coil spring of the required resiliency and strength.

The present construction is such as to increase the compression in the engine and this is 70 found to be wholly desirable in aircraft engines since when operated in high altitudes the amount of fuel mixture drawn into the cylinders decreases and the engine loses power on account of the decreased charge, but if the engine is provided 75 with a variable compression device, the weaker

the engine power output the same as is had in lower altitudes with a lesser compression even if supercharging means are used in combination therewith. Obviously, the present construction 5 may be used in engines of the compression ignition type as well as with engines of the spark ignition type.

In Fig. 5 I have diagrammatically illustrated the present invention incorporated with an in line engine and showing a plurality of cranks 35 and 36 embodied on a crankshaft 37, each of these cranks supporting eccentric sleeves or bearings 35a and 36a, said eccentric sleeves carrying weights 35b and 36b constructed in a manner 15 similar to the construction shown in Fig. 1 only with this difference that the clearance space of the pistons in the cylinders decreases if the engine speed increases. The sleeves 35a and 36a are respectively provided with gears 35c and 36c 20 which are arranged to mesh with gears 38 carried by a shaft 39 rotatably mounted in the internal bore 40 of the crankshaft. At one end of the crankshaft the shaft 39 is surrounded by a coil spring 41, one end of the coil spring being secured 25 to shaft 39 as at 41a while the other end of said coil spring is fixed as at 41b to a stub shaft 42 splined or otherwise secured to the end of the crankshaft. This stub shaft 42 may be provided with spiral threads 43 engaging complementary 30 internal spiral threads carried within the crankshaft, and is thus angularly as well as longitudinally adjusted within the crankshaft. The angular adjustment of the stubshaft 42 provides for an adjustment of the tension of said coil spring 41 35 for controlling the resistance to the movement of the counterweights and this pinion 42 may be axially shifted by a lever 44 in any suitable manner, the same being moved, if so desired, by means of a pull rod 44a. The pull rod 44a has 40 an abutment 44f acting upon an arm 75c of a three-way valve 75d, which valve controls the hydraulic means to control the automatic action to increase the compression ratio, and will be discussed in connection with Figs. 12 and 13 hereinafter.

In Fig. 6 a further modified construction is shown in which the crankshaft 50 is provided with a shaft portion 51 and the other shaft portion of the crankshaft is identified by the reference character 51a. A crank cheek 52 carries a crank pin 53 which is adapted to be connected with the shaft portion 51 by means of a crank arm 54, said crank arm being preferably formed of two sections and clamped to the end of the crank pin 53 by means of bolts or other fastening means 55. An eccentric sleeve or bearing structure 56 is mounted on the crank pin 53 and is preferably provided with an enlarged bore 57 forming an annular chamber 58 around the crank pin in which the coil spring 59 is contained. One end of the coil spring is fixed as at 59a with the eccentric sleeve while the other end of said coil spring is fixed as at 59b with the crankshaft structure. A connecting rod may be mounted on this eccentric sleeve and I have preferably illustrated a hub 60 of a master rod structure as being mounted on the sleeve, said hub carrying a plurality of knuckle pins 60a to which are connected articulating rods 61. The eccentric sleeve 70 is provided with weights 56a, these weights being urged by centrifugal force during engine operation to directly rotate the eccentric sleeves whereby to vary the relative position of the master rod hub with respect to the axis of the crank pin 53.

so that the compression ratio increases at high speeds, the adjustment of said eccentric sleeve being resisted by the coil spring 59, this spring being substantially the same as the spring of the mechanism illustrated in Figs. 1 to 4 inclusive.

The weights attached to the eccentric sleeves or bearings and the reciprocating masses attached to the hub 60 will, during the operation of the engine, assume various relative positions and thus tend to unbalance the crankshaft. To offset this unbalanced condition, it is preferable to provide movable counterweights which may be automatically adjusted by centrifugal force as shown in Figs. 4 to 8, or by centrifugal force acting on hydraulic means, but controlled by the operator as shown in Figs. 12 and 13.

In Fig. 4 there is shown weights 25b which are mounted on the crank cheeks 20 and 20a, these weights having an extension 25c extending radially inwardly towards the axis of the crankshaft and carrying a head 25d which engages a spring 25e and tends to compress the spring as the speed of the engine increases due to the centrifugal force which tends to throw the weight 25b outwardly from the axis of rotation. Thus, as the weights 30 and 30a are moved to a different position with respect to the initial position, the increased mass to that side of the crankshaft is counterbalanced by providing a mass at a greater distance from the crankshaft axis which lies diametrically opposite to the position of said weights 30 and 30a when lying in the position as shown in Fig. 4 in solid lines. Obviously as the engine speed increases the weights 30 and 30a will return toward the position shown in dotted lines and the weights 25b also will move toward the crankshaft axis and thus, the crankshaft is maintained substantially in perfect balance during all periods of the engine operation.

In Figs. 8 and 9 I have illustrated another form of counterbalancing in those constructions where a single crank is employed. The crank shaft 62 is provided with a crank pin 62a and a shaft portion 62b. 63 designates the main counterweight and 64 designates the adjustable auxiliary weights, the latter sliding in the former as shown in Fig. 9. Three shafts or rods 65 are attached to certain movable or adjustable weights, each rod provided with a spring 66 resting at one end against the main counterweight as at 67 and having its other end resting against a shoulder 67a on said rods 65. These shafts slide in a cross bar 67b which is provided with corresponding holes for the shafts and attached to the main counterweight by rivets 67c. When the engine speed increases the weights 64a carried by the eccentric sleeve 64b will be rotated from the position shown in Fig. 9 to a position diametrically opposite and thus to balance the mass of this counterweight 64a, it is necessary to provide additional mass or move the mass of the main counterweight structure further away from the axis of rotation. The weights 64a are so placed regarding the thickest part of the eccentric sleeve that the compression ratios decrease with increasing engine speeds. That means again the clearance space of the pistons in the cylinders is increased with increasing engine speeds. I prefer to provide an adjustable mass 64 which is moved outwardly from the axis of rotation as the engine speed increases, the outward adjustment of weight 64 being resisted by the springs 66, the said springs having a predetermined strength whereby to maintain the crankshaft in balance during all periods of engine operation.

In Figs. 10 and 11 the movable weights are shown as being cylindrical, the crank 68 having a main counterweight 68a, the shaft portion 69 having an oil conduit 69a which may be a part of the crankshaft lubrication system or a separate conduit. The counterweight 68a is provided with a hole or bore 71 extending perpendicular to the axis of the crankshaft 68 and crank pin 69b. The cylindrical weight 70 is contained within the hole 71 and is provided with a shoulder 70a which may have suitable oil rings 70b carried thereon for engagement with the surface of the hole 71. A spiral spring 72 engages the shoulder 70a and abuts a plug 73 secured to the counterweight 68a. As in the engine speed increases the weight 70 will move away from the axis of rotation to counterbalance the eccentricity of the weights carried by the eccentric sleeve mounted on the crank pin of the engine crankshaft. Due to the fact that the chamber provided by the bore or hole 71 is filled with oil under pressure, any sudden slowing down of the engine will force the weight 70 inwardly and the weight 70 is prevented from suddenly striking the bottom of the bore 71 due to this oil cushion.

Figs. 12 and 13 illustrate a further modified construction in which the crank 74 is provided with a shaft portion 75 and a crank pin 76. An eccentric bearing or sleeve 77 is mounted on the crank pin and a weight 77' is carried by said eccentric sleeve. In this construction the eccentricity is at a maximum, resulting in the maximum compression when this weight is positioned to the outside or diametrically opposite to the position shown by dotted lines 77a in Fig. 12 when the engine speed is high. When the weight is in the inside position as shown by dotted lines 77', the construction is such as to provide for a minimum compression in the engine when the engine speed is low. A cam 78 is carried by the eccentric sleeve and is arranged to engage a plunger 79 which in turn engages a plunger weight 80 shown in the outermost position when the engine speed is at a maximum. The plunger 80 is engaged by a heavy spring 81, said spring abutting a plug or other suitable abutment 82 secured to the weighted crank arm 83, while conduit 75b in Fig. 13 communicates with the space or chamber 81' in which the spring 81 may be contained for pure mechanical control of the adjustably supported weight. In Fig. 13 the springs 81 are omitted and the oil is under pressure in chamber 81'. The oil under pressure in this chamber together with the spring 81 thus provides the resistance for controlling the adjustment of the auxiliary weight, in this case the plunger weight 80. A master rod 84 is carried on the crank pin 76 and is provided with a suitable hub for supporting knuckle pins 85, each of which are connected with a connecting rod 86.

The action of the structure shown in Figs. 5 and 7 can be reversed as far as the position of the eccentrics is concerned with respect to the position of the weights and the construction of Figs. 5 and 7 has to be changed accordingly. The construction shown in Fig. 7 can be combined with the hydraulic arrangement of Fig. 5, if so desired.

In Fig. 13 near the lower crank arm 83a is a gear wheel 69b similar to the gear wheel 99b in Fig. 7. This pinion 69b can be geared to a pinion on an eccentric bearing 77 of Fig. 13 in order to effect the same semi-automatic action of the regulation of the compression as shown in Figs. 5 or 7, only with this difference, that the spring 75

81 simultaneously acts on the weights 77 and the movable weights, but the hydraulic control of Fig. 5 must be maintained. In order to make this possible, the cam 78 is in a position with the eccentric to the left as shown in Figs. 13 and 12 and this cam may be positioned substantially 180° with respect to the weight 77 which is shown in these figures as positioned to the right. With the above construction there is no chance of the cam 10 78 being in balance in center top position so that the centrifugal force will not move it from this dead center position. The pinion 69b will move it out of this position by the electromotor or directly by the pilot, but even without this construction the plunger 80 will always free the cam 15 78 at certain speeds.

It is understood that in the construction of Fig. 7 the cylindrical member 99h may act similarly as in Fig. 5 with an arm 75c on the three-way valve, and also that the operation of this three-way valve 15d may be accomplished independently of the throttle operation, and the construction of such a valve may be such that the communication between the oil conduit 75b 20 and the conduit 75f connected with the source of hydraulic fluid pressure is gradually opened and closed, and also the connection to the sump pipe 75e may be also gradually opened and closed, either in direct reversed proportion or independently of each other by suitable and well known valve structures. Furthermore, the gradual opening and closing of these passages may be done by means of a needle valve if so desired.

It is understood that if the general arrangement of parts as shown in Figs. 5 and 7, which positively control mechanically the action of the weights of the eccentric bearings, is combined with the structures shown in Figs. 1 and 2, that the operator can control directly the position of the weights. Combining the structure shown in Fig. 7 with the structure shown in Figs. 1 and 2, it will be noted that the electromotor positively and directly controls the action of the weights.

In general, there are three (3) major methods 45 of control; the pure hydraulic, the pure mechanical and the pure automatic. Obviously, one or more of these controls as herein illustrated and described may be combined in a manner as suggested above, the particular combination desired being dependent upon the type of motor and also the type of service to which said motor is to be placed.

The weighted crank arm 83 may be constructed in sections and as shown in the present drawings the same is constructed of two halves and secured together by means of bolts 89. The oil under pressure which is introduced into the chamber 81' by preference from another source of oil pressure than the regular oil-lubrication system of the engine the regular lubricating system and when the plunger weight is returned to its inward position by a decrease in engine speed and by the force of spring 81, the oil is merely pushed or returned to the oil sump. The three-way valve of Fig. 5 is associated with the construction of Figs. 12 and 13. The passage 75b in Fig. 13 is connected with the passage 75b in the three-way valve of Fig. 5. When the plug in the valve is rotated counterclockwise about 70 90°, the oil can escape through conduit 75b through the plug to the exit 75e and return to the sump. The oil pressure enters the valve through opening 75f and if the plug is in the position shown the oil pressure may pass into 75 conduit 75b towards the chamber 81' and prevent

the piston 80 from reaching its outer position. Therefore the valve 75d actuated by the operator controls hydraulically the movement of the piston 80 in Fig. 13 and controls thereby the angular movement of the eccentric 78 and the degree 5 of compression.

I may omit the spring 81 entirely and I may use both pressure chambers 81' and 81b to control the movement of the piston both ways hydraulically, through passages 75b and 75a as 10 shown in Fig. 13.

With reference to Fig. 7, 98 is the crankshaft which is provided with a crank pin 91 and shaft portions 99. At the left the shaft portion 99 carries internal shaft 99a having a pinion 99b at 15 the right end thereof for engagement with a pinion or gear 99c on the eccentric bearing or sleeve 99d, which is also provided with the weights 99d. A connecting rod 99e is supported by the eccentric sleeve for connection with an engine piston, the adjustment of the eccentric sleeve controlling the compression ratio in the engine so that at high speeds the clearance space of the pistons in the cylinders is decreased. A shaft 99f is provided with a spiral spline or thread 20 of a relatively steep pitch in order to decrease the rotation of shaft 99a and increase the rotations of motor 99m to effect maximum or minimum compression, and this shaft 99f is engaged with the spiral spline internal bore of the 25 internal shaft 99a. The shaft 99f is provided with a grooved pulley 99g in which an internal fork of a cylinder, having an external gear 99h on which the motor operates is mounted for rotation. The gear 99h is engaged by a gear 99k driven by a motor 99m, the motor being driven from any suitable source of electric power such as by the battery 99n, a switch 99o controlling the current to the motor. The said cylinder has at the right end a screw thread operating in a 30 component screw thread of a fixture or cup attached to the crankcase, so that rotation of said cylinder by said motor moves the cylinder into the cup, and if the electromotor is made to rotate in opposite direction said cylinder screws 40 itself out of said cup. This switch may be either automatically or manually controlled and when the motor is energized, it will be noticed that the shaft 99f is rotated by said motor and cylinder moving forwards and backwards, thus rotating 45 the shaft 99a and gear 99b which in turn drives the gears 99c for rotating the eccentric sleeve 99d. The weights 99d tend to be rotated in such a way as to move the weights outwardly when opening the throttle so that the compression is increased at high speed and therefore the motor 99m should be strong enough to control the automatic tendency of the weights to increase the compression at high speeds. It will be apparent to those skilled in the art to which my invention 50 pertains that various modifications and changes may be made therein without departing from the spirit of my invention, or from the scope of the appended claims.

It is understood that in general the same method of controlling hydraulically the tendency of the centrifugal force to change the positions of parts rotatably fixed on, or in, a rotating mechanism, may be applied on any other rotating 55 mechanism.

For instance on governors, having members tending to spread under centrifugal force (with and without resilient means, that means mere weight or weights with springs). These gov-

ernors control again valves or throttles or timing mechanism for sparks etc.

For instance on the propellers of ships which have a maximum efficiency at certain speeds, one could hydraulically regulate easily such propellers to assume a given best position at certain speeds.

For instance the propellers or blades of aeroplanes, having also a maximum efficiency at certain speeds and certain pressure or rarity of air, decreasing the grip of blades on the air so that the pitch has to be greater than when rotating at atmospheric pressure.

For instance on rotating gyroscopes, which tend to retain certain mechanism, for instance ships at certain angles. The parts on such gyroscopes could easily be rotatably fixed on the mechanism and my hydraulic system could control their position at maximum efficiency.

In fact the number of applications on various mechanisms are infinite and it is, of course, understood that applicant does not limit himself to any definite arrangement as illustrated, but may apply the essence of his method, system or mechanisms on any rotating mechanism, which could use it at an advantage.

What I claim as my invention is:

1. In an internal combustion engine, a pressure lubricating system, mechanism controlled by the application of the lubricating system thereto to regulate the engine compression ratio, and valve means controlled independent of the speed of the engine to control the application of the lubricating system to the mechanism to vary the compression ratio, said mechanism tending normally to increase the compression ratio of said engine with increased engine speeds responsive to increased throttle openings.

2. In a radial internal combustion engine, the combination with a crank shaft, a connecting rod assembly including a master rod, and a pressure lubricating system, of compression ratio regulating mechanism comprising an eccentric bearing sleeve intermediate the crank shaft and the hub of the master rod, weights operatively associated with said sleeve tending to increase the compression ratio of said engine at higher engine speeds, mechanism controlling the bearing sleeve position on the shaft, said lubricating system being associated with said mechanism and means manually controlled regulating the application of the lubricating system to the mechanism controlling the sleeve.

3. In a radial internal combustion engine, the combination with a crank shaft, a connecting rod assembly including a master rod, and a pressure lubricating system, of compression ratio regulating mechanism comprising an eccentric bearing sleeve intermediate the crank shaft and the hub of the master rod, mechanism for regulating the position of the sleeve relative to the crank shaft controlled by the pressure lubricating system, and manually controlled means for controlling the application of the lubricating system to said mechanism in such a way that the compression of said engine is increased if the pressure in said lubricating system is decreased.

4. In a radial internal combustion engine, the combination with a crank shaft, a connecting rod assembly including a master rod, and a pressure lubricating system, of compression ratio regulating mechanism comprising an eccentric bearing sleeve intermediate the crank shaft and the hub of the master rod, a spaced housing secured to the crank shaft, a plunger in the housings con-

trolling the sleeve, said crank shaft having ducts therein for conducting lubricant from the system to the housing and from the housing, and means manually controlled and independent of the speed of the engine for controlling the ducts to control the position of the piston in the housing said latter means controlling said compression ratio regulating mechanism in such a way that decreased oil pressure therein increases the compression of the engine and decreases the clearance space of the pistons in the cylinders of said engine.

5. In a radial internal combustion engine, the combination with a crank shaft, a connecting rod assembly including a master rod, and a pressure lubricating system, of compression ratio regulating mechanism comprising an eccentric bearing sleeve intermediate the crank shaft and the hub of the master rod, said bearing sleeve having a transversely extending arm, a housing fixed to the crank shaft, a plunger in the housing, the bearing sleeve arm, manually controlled means for connecting the lubricating system with the housing said latter means controlling said compression ratio regulating mechanism in such a way that decreased oil pressure therein increases the compression of the engine and decreases the clearance space of the pistons in the cylinders of said engine.

6. In a radial internal combustion engine, the combination with a crank shaft, a connecting rod assembly including a master rod, and a pressure lubricating system, of compression ratio regulating mechanism comprising an eccentric bearing sleeve intermediate the crank shaft and the hub of the master rod, a housing in an arm of the crank shaft, a plunger in the housing controlling the sleeve, said crank shaft arm having duct means connecting the lubricating system with the housing and for conducting lubricant from the housing, and manually controlled means to control the flow of lubricant to and from the housing said latter means controlling said compression ratio regulating mechanism in such a way that decreased oil pressure therein increases the compression of the engine and decreases the clearance space of the pistons in the cylinders of said engine.

7. In a radial internal combustion engine, the combination with a crank shaft, a connecting rod assembly including a master rod, and a pressure lubricating system, of compression ratio regulating mechanism comprising an eccentric bearing sleeve intermediate the crank shaft and the hub of the master rod, a housing in the crank shaft, a plunger in the housing controlling the eccentric sleeve, duct means leading from the lubricating system to the housing and from the housing, a valve manually operated controlling the flow of lubricant to and from the housing, said manually operated means resisting the effect of centrifugal force upon the said eccentric sleeve said latter means controlling said compression ratio regulating mechanism in such a way that decreased oil pressure therein increases the compression of the engine and decreases the clearance space of the pistons in the cylinders of said engine.

8. In a radial internal combustion engine, the combination with a crank shaft, a connecting rod assembly including a master rod, and a pressure lubricating system, of compression ratio regulating mechanism comprising an eccentric bearing sleeve intermediate the crank shaft and the hub of the master rod, weights on said sleeve tending

- to increase the compression ratio of said engine when the engine speed increases, a housing in the crank shaft, a plunger in the housing controlling the eccentric sleeve, duct means leading from the lubricating system to the housing and from the housing, a valve controlling the flow of lubricant to and from the housing, said valve manually operated.
9. In a radial internal combustion engine, the combination with a crank shaft, a connecting rod assembly including a master rod, and a pressure lubricating system, of compression ratio regulating mechanism comprising an eccentric bearing sleeve intermediate the crank shaft and the hub of the master rod, weights on said sleeve tending to increase the compression ratio of said engine when the engine speed increases, a housing fixed to the crank shaft, a plunger in the housing, duct means leading from the lubricating system to the housing and from the housing, a valve regulating the lubricant flow to and from the housing to regulate the mechanism and cause a variable compression ratio, said valve manually controlled.
10. In an internal combustion engine the combination with a pressure lubricating system, of compression ratio regulating mechanism comprising an eccentric master rod bearing, a shaft connected with the bearing, a plunger in a housing in said shaft, duct means in the shaft communicating with the housing on opposite sides of the said plunger, and a valve controlling the duct means to establish communications with the lubricating system with the housing on either side of the plunger and simultaneously allowing discharge from the said system, said valve being manually controlled.
11. An internal combustion engine, a crank-shaft, a cylinder, a piston reciprocating therein, mechanism connecting the piston with the crank-shaft including compression ratio changing mechanism to increase the compression ratio at any speed of which the engine is capable and in response to centrifugal force, and means, subject to the control of the operator, to control said increase of the compression.
12. In an internal combustion engine, a crank-shaft, a cylinder, a piston reciprocating therein, a crankpin on said crankshaft, an eccentric sleeve on said crankpin, centrifugal weights on said sleeve tending to rotate said eccentric sleeve in such a direction that the compression is increased, and additional means, subject to the control of the operator, to control said increase of the compression ratio.
13. In a radial engine, having its cylinders arranged radially around said crankshaft, a compression ratio changing device comprising an eccentric sleeve intermediate the crankshaft pin and a connecting rod-bearing of a connecting-rod-structure, and means consisting of weights actuated in response to centrifugal force and pivotally connected to said crankpin for ad-
- justing the sleeve on the crankpin, and means, subject to the control of the operator, to control the increase of the compression ratio in response to centrifugal force.
14. The combination of claim 11, in which said means consist of hydraulic means associated with said crankshaft.
15. The combination of claim 12, in which said means comprise a lubricating system for said crankshaft and hydraulic means associated with said lubricating system to control said mechanism to increase the compression ratio.
16. The combination of claim 13, in which said means comprise in combination a hydraulic cylinder constructed in said crankshaft, and means to send a hydraulic pressure from a source of hydraulic pressure outside said crankshaft, to said cylinder to actuate a piston therein, to check the movement of said weights to increase the compression ratio.
17. In a radial type explosion engine, the combination with the crankshaft and multiple connecting rod structure, of a compression ratio changing device comprising an eccentric sleeve intermediate the crankshaft pin and the connecting rod bearing, and means consisting of weights actuated in response to the engine speeds and pivotally connected to said crankshaft at a point on the other side of the axis thereof diametrically opposite said sleeve and attached to the crankshaft for adjusting the sleeve on the crankpin, and means, subjected to the control of the operator, to prevent said adjustment.
18. In a radial type explosion engine, the combination with a counterweighted crankshaft and connecting rod structure, of a compression ratio changing device comprising an eccentric sleeve intermediate the crankshaft and the connecting rod hub, an eyebolt pivoted to the crankshaft and means consisting of weights actuated in response to the engine speed and carried by said eyebolt to control the position of the sleeve, and means under the control of the operator to check said control of said position of said sleeve.
19. In an internal combustion engine, a crank-shaft, a cylinder, a piston reciprocable in the cylinder, an inlet manifold system having throttling means which control the power output in a standard way, whereby the speed of the engine increases when the throttle is opened and decreases normally when the throttle is closed, mechanism connecting the piston with the crank-shaft including compression ratio changing mechanism to increase the compression with increase of engine speed when the charges to the cylinder increase in volume on account of said throttle opening, and hydraulic means to control the increase of compression and operating on said compression ratio changing mechanism, said hydraulic means subject to the control of the operator.

JEAN A. H. BARKEIJ.
